(57) **CLAIM**

The ornamental design for a support frame for steam pocket, as shown and described.

DESCRIPTION

FIG. 1 is a top, front and left side perspective view of the support frame for steam pocket;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof; and,

FIG. 7 is a rear elevational view thereof.

The broken lines shown are included for illustrative purposes only form no part of the claimed design.
